H. SYMES.

VARIABLE RESISTANCE, ELECTROMAGNETIC DRILLING MACHINERY.

APPLICATION FILED MAY 29, 1915.

1,219,190.

Patented Mar. 13, 1917.

UNITED STATES PATENT OFFICE.

HENRY SYMES, OF MORNINGTON, NEAR DUNEDIN, NEW ZEALAND

VARIABLE-RESISTANCE, ELECTROMAGNETIC DRILLING MACHINERY.

1,219,190.

Specification of Letters Patent. Patented Mar. 13, 1917.

Application filed May 26, 1915. Serial No. 30,877.

To all whom it may concern:

Be it known that I, HENRY SYMES, of Mornington, subject of His Majesty the King of Great Britain, residing at Mornington, near the city of Dunedin, in the British Dominion of New Zealand, inventor, have invented certain new and useful Improvements in Variable-Resistance, Electromagnetic, Drilling Machinery, of which

10 the following is a specification.

The object of this invention is to furnish a portable drilling set that is operated by a branch taken off the usual high power electrical current carrying cables, or other 15 electrical supply sufficiently powerful for the purpose, also to show means whereby the drilling set is kept to its work by electromagnetic means, causing the drilling frame to adhere to the metal surface to be 20 drilled; thus doing away with the knees, cramps or chain devices now necessary to keep the drill pressed to the work to be drilled.

The drill itself may be worked by hand 25 or flexible shaft or other suitable power instead of electricity if desired, and fed to its work either by hand or automatically in the usual way, or drawn down to its work by a solenoid, all electrical currents 30 being supplied with a variable resistance device so as to lessen the power when same could be done, thus obviating the heating that would result from a continuous high power electrical current passing through 35 the various cables and bobbins. Where the drill is worked forward by a solenoid, a trip would be provided lessening the power and closing it off as the hole was about through, or deep enough.

40 The accompanying drawing illustrates an elevation of a variable resistance electromagnetic drilling machine embodying the features of the invention.

The machine comprises a frame A provided with a yoke A² having members A³. A' represents the device or article to be drilled.

B is a drill of any usual make fixed to C the usual drilling spindle and holder 50 which engages the frame A and yoke A². The spindle or holder has a sliding feather

or key C' to allow of the drill ascending or descending. D are gear wheels but obviously any other suitable forms of gear could be used. E E is a double electro-magnet actuated by the electrical current through E¹. F F is the solenoid capable of drawing in the drill spindle by yoke on C in the direction of the arrows, and so drilling. The electrical current passing through the wires F¹ F² and the variable resistance device E². F² and E² show these devices which would be included in all currents as mentioned. G is the usual electrical drilling motor fed by variable resistance 60 electricity at G¹.

As my object in this invention is to apply a variable resistance current of electricity to electro-magnets to cause the drilling frame to adhere to the metal work to be drilled, and also to feed as well as drive the drill by the same currents, all capable of alteration in intensity, as needed, the exact form of drilling frame is immaterial, but I have set forth suitable ones for my 70 purposes. The switching on and off of the various currents or branches would be in the usual manner and so as to be independent of each other. In this invention any suitable materials or sizes may be adopted. 80

Having described and explained my invention what I desire to obtain in a patent of the United States of America, is:—

1. In electro-magnetic drilling machinery, the combination of a frame having extremities forming solenoids, a drill spindle rotatably mounted in the frame and provided with operating means, electro-magnets applied over the solenoids, portions of the solenoids projecting beyond the electro-magnets to provide attractive means relatively to the work to hold the drilling machinery in place, and means for feeding a variable resistance current through the solenoids to set up a direct pull by means of the latter, the variable resistance current being operable to lessen the power thereof when desired. 85

2. In electro-magnetic drilling machinery, the combination of a frame having a yoke members forming solenoids, electro-magnets engaging said solenoids, a drill

spindle rotatably and slidably mounted in relation to the frame carrying the drill, the solenoids and the electro-magnets thereof operating to draw the spindle and drill closely to the work, an electric motor connected to and operating the drill spindle, and means for feeding a variable resistance

current through the solenoids to set up a direct pull by means of the latter, the said variable resistance current being reducible to obviate heating.

In testimony whereof I have hereunto set my hand.

HENRY SYMES.
